UNITED STATES PATENT OFFICE.

HARDY H. HAIR, OF NEWPORT BEACH, CALIFORNIA, ASSIGNOR TO FLOYD G. WHITE,
TRUSTEE, OF LOS ANGELES, CALIFORNIA.

DEVICE FOR TAKING CORE SAMPLES IN ROTARY DRILLING.

Application filed February 27, 1922. Serial No. 539,392.

To all whom it may concern:

Be it known that I, HARDY H. HAIR, a citizen of the United States, residing at Newport Beach, in the county of Orange and State of California, have invented new and useful Improvements in Devices for Taking Core Samples in Rotary Drilling, of which the following is a detailed specification.

10 The nature of the invention will be best understood from the following detailed and specific description of preferred forms and specific arrangements of mechanisms embodying the invention, reference for that purpose being had to the accompanying drawings in which:

Fig. 1 is a view partly in elevation and partly in longitudinal section showing my core taking apparatus applied to one form 20 of rotary drilling bit; Fig. 2 is a bottom plan view of the same; Fig. 3 is an enlarged sectional detail showing the upper end of the core taking tube with its valve.

In Figs. 1 and 2 I show a form of rotary bit that embodies a mandrel 10 carrying two cutting disks 11. This illustration may be taken as typical of any of the rotary drilling bits embodying a mandrel and cutters. I mount a core taking barrel 12 in the lower part of the bit, centrally located as illustrated between the cutters. This barrel may be made for instance of a piece of heavy hydraulic pipe having at its lower end a shoe 14 with cutting teeth 15. These teeth may 35 of course be made directly on the lower end of barrel 12 itself but I prefer to provide a shoe as that facilitates sharpening of the cutting teeth and also facilitates the change in effective length of the barrel so that it 40 may be made to project a greater or lesser distance below the lower edges of cutter 11. For instance, shoes 14 of different lengths may be provided for this purpose. In different kinds of formations, hard or soft, it 45 is desirable to have the cutting teeth project a lesser or greater distance below cutters 11.

The core taking barrel is extended upward in any suitable manner so that a core of any desired length may be taken. For 50 instance, the barrel may be extended upward through the mandrel and above it as at 17, and then extended further if desired by an extension 18 of which any number of joints may be supplied so that the effective 55 length of the barrel may be made as desired.

The internal diameter of all these parts is preferably the same so that the core that enters at the bottom of barrel 12 may pass upward with the least disturbance.

At the upper end of the extended barrel 60 an upwardly opening valve 25 is placed. This valve may embody a downwardly seating ball 26 in a cage 27 and pressed down by a spring 28 to make sure that it will seat. the spring being strong enough to press the ball onto its seat through any mud that may be under the ball. In order to insure proper action of the spring its lower end is welded or otherwise permanently secured to spring seat 29 that fits on top the ball. The action 65 of this ball valve is to allow water or any other substances to pass upwardly out of the upper end of the core taking barrel; but when the valve is seated it will prevent a core that is in the barrel from dropping out. 70

In order further to facilitate vertical adjustment of the core barrel, and to hold the barrel rigidly to its set height, the mandrel 10 is shown split on the central plane 10^a and is held together by the tool joint 10^b. 80 Barrel 12 has one or more external ribs 40 that fit in corresponding annular grooves 41 in the mandrel, which grooves are so spaced that the barrel may be adjusted up and down by placing the rib or ribs in different grooves. The vertical position of the lower cutting end of the barrel may be thus adjusted to suit different formations and to compensate wear on the cutting edge 15. The mandrel halves may clamp the barrel tightly enough to prevent its slipping rotatively or any suitable means may be used to prevent such slipping. 85

The bit thus equipped with my core taking device is used in the ordinary manner. 90 As the core barrel projects a little below the cutters it is of course at all times cutting directly into the formation at the bottom of the hole; and as the bit is lowered a core from the formation is forced up through the barrel. Thus if it is not desired to obtain a sample this core is merely continuously pushed up through the barrel and out its upper end where it enters the stream of water passing down through drill stem 30 and is carried by that stream of water downwardly through the bit through the water passages 31. When however, a sample is desired the drilling operation is stopped and the bit raised to the surface. The core bar- 100 105 110

red then of course shows the sample of the last formation drilled through; and the vertical extent of the formation that will be represented in the taken core will of course depend upon the vertical length of the barrel. The core may be removed from the barrel in any suitable manner as by pushing it out endwise, the valve 25 being taken off for this purpose so that the core comes out ²⁵ 10 undisturbed.

The inner diameter of shoe 14, as indicated at 14^a, is preferably less than the inner diameter of the barrel, so that the core cut by the shoe will pass easily up through ²⁵ 15 the barrel; and if desired there may be another slight enlargement in diameter at the extension 17 for the same purpose.

From these illustrations it will be apparent how my core taking device may be applied to various other forms of rotary drill- ²⁵ 20

ing bit. Accordingly, I do not limit my invention to the specific adaptations here illustrated, nor to the specific construction herein described, as the device may be varied to adapt it to different situations. ²⁵

Having described a preferred form of my invention, I claim:

In combination with a rotary drilling bit, split longitudinally, and having a central vertical passage, a core taking barrel clamped between the bit halves in the vertical passage, the passage having a plurality of spaced recesses and the barrel having a projection adapted to register with any one of the recesses to hold the barrel at different heights in the bit.

In witness that I claim the foregoing I have hereunto subscribed my name this 14 day of Feb., 1922.

HARDY H. HAIR.
